UNITED STATES PATENT OFFICE.

OSKAR GRAUHEDING, OF DUSSELDORF, GERMANY, ASSIGNOR TO RHEINISCHE METALL-WAAREN- UND MASCHINENFABRIK, OF DUSSELDORF- DERENDORF, GERMANY, A CORPORATION OF GERMANY.

TELESCOPIC SIGHT PROVIDED WITH VARIABLE SIGHTING-POINTS.

1,135,787.

Specification of Letters Patent.

Patented Apr. 13, 1915.

Application filed October 19, 1914. Serial No. 867,417.

To all whom it may concern:

Be it known that I, OSKAR GRAUHEDING, engineer, a subject of the German Emperor, residing at 26 Fischerstrasse, Dusseldorf, 5 Germany, have invented certain new and useful Improvements in Telescopic Sights Provided with Variable Sighting-Points; and I do hereby declare the following to be a full, clear, and exact description of the invention, such as will enable others skilled in the art to which it appertains to make and use the same.

The present invention consists in further modifications of the sighting devices for a 15 telescope described in Letters Patent No. 1,004,416, dated September 26, 1911.

The invention consists in providing means for separately adjusting the position of the sighting marks, which enables the sighting 20 points to be set in the field of view of the telescope according to range.

In the accompanying drawings, Figure 1 represents a cross section and Fig. 2 a side view of an example of a construction according to the invention. Fig. 3 shows a side view of another construction of the adjusting device. Figs. 4 and 5, are respectively, 25 a cross section and elevation, with parts in section, of a slight modification.

30 The different sighting marks are placed in radially movable separate frames *b* mounted in a main frame *a* which is eccentric to the optic axis. The frames *b* carrying the marks can be raised or lowered relatively to 35 the optic axis by adjusting screws *c*¹ and *c*² engaging opposite points of said frames. In this way, the optical angle of elevation can be exactly adjusted for every range by observation when the gun is fired. Every time 40 the gun is fired, the exact position of the point of intersection can be again determined. The pin *d*, which is under spring pressure, holds the main frame *a* in every position in which it may be set. The frame 45 can be easily turned by hand by a milled wheel or other means, and each sighting mark, as it may be required, can be brought into the field of view of the telescope. The sighting marks can in known manner be 50 etched on glass, as shown in Figs. 1 to 3, or

formed by wires, as shown in Figs. 4 and 5. The corresponding range number is shown in Figs. 1 to 3 under each sighting mark.

The sighting marks need not be arranged in the construction shown, but, as indicated 55 in Fig. 3, different constructions may be used to suit the disposition of the eccentrically arranged disk on which the marks are placed. To suit this eccentric position, instead of the radial arrangement screws 60 shown in Fig. 22, they may be set tangentially as shown in Fig. 3.

In Figs. 4 and 5 the sighting marks *e* are wires set in radially arranged screw plugs *f*, which are designed to be adjusted within the 65 main frame *a*.

I claim as my invention:

1. A sight comprising a telescope, a series of sighting marks, separate supports for said marks, and a main frame carrying said 70 supports mounted in said telescope eccentrically to the optic axis thereof.

2. A sight comprising a telescope, a series of sighting marks, a separate frame for each mark, and a main frame in which the mark- 75 carrying frames are mounted, said main frame being mounted in said telescope eccentrically to the optic axis thereof.

3. A sight comprising a telescope, a series of sighting marks, a separate frame for each 80 mark, a main frame in which the mark-car- rying frames are mounted, said frame being mounted in the telescope eccentrically to the optic axis thereof, and means for separately adjusting the mark-carrying frames. 85

4. A sight comprising a telescope, a series of sighting marks, a separate frame for each mark, a main frame in which the mark-car- rying frames are mounted, said main frame being mounted in the telescope eccentrically 90 to the optic axis thereof, and adjusting screws mounted in said main frame and engaging the separate frames.

In testimony whereof, I have signed this specification in the presence of two subscrib- 95 ing witnesses.

OSKAR GRAUHEDING. [L. S.]
